US0D1086926S

(12) **United States Design Patent** (10) **Patent No.:** **US D1,086,926 S**
(45) **Date of Patent:** **** Aug. 5, 2025**

(54) **BRACELET**

(71) Applicant: **Yisong Huang**, Yulin (CN)

(72) Inventor: **Yisong Huang**, Yulin (CN)

(**) Term: **15 Years**

(21) Appl. No.: **29/955,296**

(22) Filed: **Jul. 31, 2024**

Related U.S. Application Data

(62) Division of application No. 29/934,669, filed on Mar. 27, 2024, now Pat. No. Des. 1,041,341.

(51) **LOC (15) Cl.** **11-01**

(52) **U.S. Cl.**
USPC **D11/13**

(58) **Field of Classification Search**

USPC D11/1-5, 26

CPC A44C 5/12
